CONTROL PANEL FOR DATA ACCESS
ACOUSTIC COUPLER

John P. Kennedy, Columbus, Ohio, assignor to
Design Elements, Inc.

Filed Apr. 20, 1972, Ser. No. 246,108

Term of patent 14 years

Int. Cl. D14—03

U.S. Cl. D26—14 A

FIG. 1 is a top view of the control panel for data access acoustical coupler showing my new design,

FIG. 2 is a first side view of the panel of FIG. 1;

FIG. 3 is another side view of the panel of FIG. 1; and

FIG. 4 is the control panel of the design in its operational environment, the broken lines are shown for illustrative purposes only.

I claim:

The ornamental design for control panel for data access acoustic coupler, as described.
